MULTI-LEVEL THREE POD STORAGE HANGAR FOR AIRCRAFT

Robert W. Fairburn, Suite 1100, 100 W. Clarendon,
Phoenix, Ariz. 85013

Filed May 21, 1973, Ser. No. 361,967

Term of patent 14 years

Int. Cl. D25—03

U.S. Cl. D13—1 E

FIG. 2

FIG. 3

FIG. 4

FIG. 5

FIG. 1 is a perspective view of the left side, top and front view of a multi-level three pod storage hangar for aircraft;

FIG. 2 is a right end view of the hangar shown in FIG. 1;

FIG. 3 is a back view of the hangar shown in FIGS. 1 and 2;

FIG. 4 is a top view of the hangar shown in FIG. 1; and

FIG. 5 is an enlarged partial view of one corner of one of the pods of the hangar shown in FIG. 1.

I claim:

The ornamental design for a multi-level three pod storage hangar for aircraft, as shown and described.
